UNITED STATES PATENT OFFICE.

JOHN LINES, OF WATERBURY, CONNECTICUT, ASSIGNOR TO THE SCOVILL MANUFACTURING COMPANY, OF SAME PLACE.

DESIGN FOR A GAS-BURNER.

SPECIFICATION forming part of Design No. 26,036, dated September 15, 1896.

Application filed May 27, 1896. Serial No. 593,347. Term of patent 7 years.

To all whom it may concern:

Be it known that I, JOHN LINES, of Waterbury, in the county of New Haven and State of Connecticut, have invented a new Design 5 for a Burner; and I do hereby declare the following, when taken in connection with the accompanying drawing and the letters of reference marked thereon, to be a full, clear, and exact description of the same, and which 10 said drawing constitutes part of this specification, and represent a view in side elevation of a burner containing the several features of my design.

This invention relates to a design for burners; and the design consists in the configuration and ornamentation of the burner, as 15 herein shown and described.

My newly-designed gas-burner comprises 20 three original features, namely, an air-chamber of flattened form, a perforated burner-skirt, and serpentine uprights.

The said air-chamber comprises a dome-like upper portion A and a concave lower portion A', terminating in a knurled band 25 A'', the whole form of the chamber being flattened rather than spherical. The perfor-

rated skirt B is cup-like in form, and contains many perforations B', which are relatively small, and several relatively large perforations B''. The bottom of this skirt rests upon 30 the dome-like upper portion A of the air-chamber, while its top supports the chimney-gallery C. The serpentine uprights D are supported at their lower ends in the gallery C and connected at their upper ends by 35 means of a coupling-ring D', above which they project for the reception of the shade-holding arms D''. I call these uprights "serpentine" uprights, because they are truly serpentine in form, their inner as well as 40 their outer edges being wavy or serpentine.

I claim—

The design for a gas-burner as herein shown and described.

In testimony whereof I have signed this 45 specification in the presence of two subscribing witnesses.

JOHN LINES.

Witnesses:
